United States Patent Office

Des. 204,415

Patented Apr. 12, 1966

204,415

RIVET

John K. Barry, Springfield, Pa., assignor to South Chester Corporation, Lester, Pa., a corporation of Delaware

Filed Nov. 12, 1963, Ser. No. 77,369

Term of patent 14 years

(Cl. D54—9)

FIG. 1

FIG. 2

FIG. 4

FIG. 3

FIG. 5

FIG. 1 is a top plan view of a rivet embodying my new design;

FIG. 2 is an elevational view thereof;

FIG. 3 is a bottom plan view thereof;

FIG. 4 is an elevational view of a slightly modified form of rivet embodying my design in which the shank is not split; and

FIG. 5 is a bottom plan view of the modified rivet of FIG. 4.

This is a continuation-in-part of design application Serial No. 65,914 filed July 13, 1961, now abandoned.

I claim:

The ornamental design for a rivet, as shown and described.
